J. W. BAKER

BOX

Filed June 24, 1922

Inventor
J. W. Baker.

Attorney
A. B. B. J.

UNITED STATES PATENT OFFICE.

JAMES W. BAKER, OF DOTHAN, ALABAMA.

BOX.

Application filed June 24, 1922. Serial No. 570,600.

To all whom it may concern:

Be it known that I, JAMES W. BAKER, a citizen of the United States, residing at Dothan, in the county of Houston and 5 State of Alabama, have invented certain new and useful Improvements in a Box; and I do hereby declare the following to be a full, clear, and exact description of the invention, such as will enable others skilled in the 10 art to which it appertains to make and use the same.

The invention provides a box which answers the two fold purpose of a depository for orders, tickets, slips and the like and 15 as an advertising medium and desk, the latter providing convenient means for supporting the order blanks while filling in the same and displaying the matter to be brought to the attention of the public. 20 Other objects and advantages will be apparent and suggest themselves as the nature of the invention is understood.

While the drawing illustrates an embodiment of the invention it is to be understood 25 that in adapting the same to meet different conditions and requirements, various changes in the form, proportion and minor details of construction may be resorted to without departing from the nature of the 30 invention.

Referring to the accompanying drawing forming a part of the specification,

Figure 1 is a perspective view of a device embodying the invention,

Figure 2 is a vertical central longitudinal section, and

Figure 3 is a transverse section on the line $x-x$ of Figure 2 looking to the left as designated by the arrows.

Corresponding and like parts are referred to in the following description and designated in the several views of the drawing by like reference characters.

The device comprises an elongated base 45 formed of longitudinal strips 1 and end strips 2. An intermediate strip 3 is located near one end of the base and cooperates with the adjacent end strip to support the box 4. The sides of the box 4 project slightly beyond the sides of the longitudinal strips 1. The top 5 of the box is hinged and when closed is secured by any suitable locking device, a hasp or pad lock 6 being shown. An opening is provided in the top 5 to receive 50 orders, tickets, slips and the like to be deposited in the box. The front of the box 4

consists of a glass plate 7 which admits of the interior of the box being under observation so that orders deposited therein may be seen to insure due collection. 60

A glass plate 8 forms the top of the base to one side of the box 4 and rests upon the longitudinal strips 1 and the end strip 2 remote from the box 4. Cross pieces 9 support the inner end of the glass plate 8 and the intermediate portion thereof and are secured at their ends to the longitudinal strips 1. Side strips 10 are secured to the longitudinal strips 1 and project above the latter a short distance and are formed in their inner faces with grooves to receive the longitudinal edges of the glass plate 8. An end strip 11 is attached to the outer end strip 2 and projects above the upper edge thereof a short distance, the projecting portion being 70 grooved to receive the outer end of the plate 8. The bottom of the box 4 engages the inner end of the plate 8 to prevent inward movement thereof. The strips 10 and 11 are removable whereby to admit of detachment 75 of the glass plate 8. A card 12 is placed beneath the glass plate 8 and is provided with suitable advertising matter to be displayed. The card 12 may be readily replaced by removing the glass plate 8 as will 80 be readily understood.

Order blanks in tablet form may be attached to the device as indicated at 13. The attaching means may consist of a chain 14 or like part. The base constitutes convenient means for supporting an order blank, 85 sheets or cards when writing thereon besides containing advertising matter to be brought to the attention of the public. The device may be placed in any convenient position frequented by the public and provides convenient means for receiving orders for laundry or other work, such orders being collected at stated intervals which may be suitably designated on a convenient part of 90 the device.

Having thus described the invention, what I claim is:

1. A device of the class described having a base, a deposit box supported thereon, the base having an extension beyond said box, advertising means supported on the extension and overlapped at one end by the box, said advertising means including a plate to constitute a desk top, and side strips and an end strip detachably secured to said extension to overlap and retain said adver- 105 110

tising means in place in combination with the box.

2. A device of the class described having a base, a deposit box supported thereon, 5 said base having an extension beyond the deposit box, said base including an end strip and a cross piece, an advertising card resting on said end strip and cross piece, a transparent panel above said card, side 10 strips and end strips provided with grooves receiving said panel, means detachably securing said side strips and last mentioned end strips to said extension, the bottom of the box being disposed relatively close to 15 one end of the card and panel to coact with

the first mentioned end strip in order to prevent longitudinal displacement of the card and panel, and a portion of the box being disposed directly over said cross piece and adjacent ends of the card and panel and 20 depending below the upper surfaces of the side strips and being substantially in contact with the panel.

In testimony whereof I affix my signature in presence of two witnesses.

JAMES W. BAKER.

Witnesses:

W. J. BOXLEY,
JOHN W. ROLLINS.
